QUICK STARTING ARRANGEMENT FOR
FLUORESCENT LAMPSMorton Berland and Melvin Spiegler,
St. Paul, Minn.

Application December 12, 1949, Serial No. 132,565

2 Claims. (Cl. 315—100)

1

This invention relates to glow discharge devices, and more particularly a quick starting arrangement for fluorescent lamps or other electric discharge tubes having a gaseous filling.

An object of the present invention is to provide an arrangement for glow discharge devices in which the time required for starting the discharge is substantially reduced.

Since the cathode of a hot cathode tube must be heated to a sufficiently high temperature before a glow discharge or light producing discharge can be started in the tube, it is a further object of the invention to provide means to maintain the electrodes of the fluorescent lamp or other tube in a heated condition at all times so that the light producing discharge can be formed in the tubes almost instantly upon closing of the selector switch provided for that purpose.

Yet another object of the invention is to provide a novel relay device comprising a glow tube in which a standard minimum time relay required to cause a thermostatically operated pair of contacts to open within the glow tube is provided.

Still another object of the invention is to provide a novel relay means including a glow tube having thermostatically controlled contacts therein, which is highly efficient in operation, simple in construction and manufacture, and adapted to provide means for starting a fluorescent lamp with a minimum time delay.

Still further objects reside in the provision of another arrangement for quick starting of a fluorescent lamp which consists in providing suitable relays in conjunction with the ballast in an operative circuit adapted to produce a high electromotive force across the electrodes of the fluorescent lamp to ignite it immediately.

These, together with the various ancillary objects of the invention which will become apparent as the following description proceeds, are attained by these quick starting arrangements for glow discharge devices, several preferred embodiments of which have been illustrated in the accompanying drawings, wherein:

Figure 1 is a circuit diagram showing the arrangement of the glow discharge device and quick starting arrangement therefor within one type of fixture;

Figure 2 is another circuit diagram similar to that of Figure 1, but showing an alternate arrangement of the elements of the invention;

Figure 3 is a circuit diagram of another form of quick starting arrangement using a relay actuated switch to provide a high electromotive force in conjunction with the ballast;

2

Figure 4 is another relay arrangement similar to that of Figure 3, this time however using a pair of current limiting devices in series with the glow discharge device; and

Figure 5 is a still further circuit diagram showing another starting arrangement for a glow discharge device.

With continuing reference to the accompanying drawings wherein like reference numerals 10 designate similar parts throughout the various views, reference numeral 10 is used to generally designate a fluorescent lamp fixture, shown schematically by dotted lines, on which a fluorescent tube 12 having electrodes 14 and 16 is adapted to be operatively emplaced. Supported within the fixture 10 is a glow lamp or tube 18 having electrodes 20 and 22 therein. Depending within the glow tube 18 is a conductor having a contact 24 thereon. A bimetallic conductor 26 having contact 28 attached thereto is also positioned within the glow tube 18. Contacts 28 and 24 of tube 18 are electrically connected to the electrodes 14 and 16. The ballast 30 or impedance adapted to control the flow of current is, as is conventional, connected in series with the tube 12. The electrode 20 of the glow tube 18 is connected through a suitable conductor to the line 32. A current limiting device 34 such as a choke, resistor, condenser or the like is placed in parallel with a shunt 36 which has a manually operated switch 38 therein. Line voltage is applied across the leads 40 and 42 which are connected to a suitable power source.

When light is not desired, the manually operated switch 38 is in the off position. Contacts 24 and 28 are in the closed position. Current flows through the current limiting device 34, the ballast 30, the electrode 14, the contact 28, the contact 24, electrode 16, and the lead 42. This will keep the electrodes 14 and 16 always at or near operating temperature. The purpose of the choke 34 is to limit the current through the electrodes 14 and 16 to such values as not to cause the electrodes to burn out too rapidly while permitting current flow of such nature as will not cause the tube to ignite. The current limiting device 34 is in series with the ballast 30, the voltage across the ballast is insufficient to cause the tube 18 to glow, therefore, the contacts 24 and 28 will remain closed.

When light is desired, switch 38 is turned to a closed position, thus shorting out the current limiting device 34 and causing the line current to increase. This will cause an increased voltage across the ballast 30 which will be sufficient to

cause glow lamp 18 to glow. The heat of the glow lamp will cause the bimetallic member 26 to bend thus opening contacts 24 and 28 and creating a high back electromotive force from ballast 30 across electrodes 14 and 16 which ignites the lamp 12 causing it to fluoresce.

The size of the glow lamp 18 and the bimetallic conductor 26 are so designed as to open the contacts 24 and 28 as quickly as possible without being so sensitive that the contacts open and close when they are not desired to.

To turn off the lights, the switch 38 is then turned to an off position so that the line current will flow through the current limiting device 34 dropping the voltage across the ballast 30. Thusly, since the voltage across the ballast is now insufficient to keep the glow lamp 18 activated, the bimetallic member 26 cools off so that the contacts 24 and 28 will close which causes the fluorescent lamp 12 to stop emitting visible light.

An alternative form of connection of this device is shown in Figure 2. However the elements of the device are encased within a fixture 58 and have been arranged in a different manner. In this embodiment, a resistance 52 is connected in series between the electrode 22 of the glow lamp 18 and the lead 42. As can be readily seen, when switch 38 is open, the voltage across 32 and 42 is insufficient to cause the glow lamp 18 to glow. Therefore, contacts 24 and 28 remain closed which will allow electrodes 14 and 16 to be heated yet prevent the lamp 12 from fluorescing. When switch 38 is closed the voltage across 32 and 42 will then become the line voltage across 40 and 42 so as to cause the glow lamp 18 to glow, heating up a bimetallic member 26 and causing the contacts 24 and 28 to part. Thusly, because of the ensuing high electromotive force the lamp 12 will be ignited.

Referring now in particular to Figure 3; it will be seen in this case that the glow lamp 18 is eliminated and a relay formed by a solenoid 62, connected in parallel with the series combination of the lamp 12 and ballast 30, and operating switch 64 is provided. The switch 64 is connected in circuit between conductors connecting electrodes 14 and 16. When the switch 38 is open, current applied to solenoid 62 will be insufficient to actuate the relay and contacts will remain in the normally closed position. However when the switch 38 is closed, the switch 64 will spring open, thus causing the high back electromotive force across the electrodes 14 and 16. This connection is shown schematically and placed within a casing 60 shown by dotted lines.

Yet another species of quick starting arrangement which may be mounted within a fixture 70 shown schematically by dotted lines, is shown in Figure 4. In this arrangement, solenoid 72 actuates switches 74 and 76 which are connected in circuit with current limiting devices 78 which limits current to electrode 16, and 80 which limits current to electrode 14. Switches 74 and 76 form a double pole single throw switch. When light is not desired switches 74 and 76 are closed and current flows through the filaments 14 and 16, keeping them at or near operating temperature. When light is desired, switches 74 and 76 are opened and the high electromotive force produced by the ballast 30 will cause the lamp 12 to ignite and fluoresce immediately. The relay formed by the solenoid 72 and the switches 74 and 76 is operated as follows; switch 81 is opened momentarily causing the relay 72

to throw switches 74 and 76 to a closed circuit position. Momentarily closing switch 81 again will open the switches 74 and 76. However, switch 81 can be eliminated and a manually operated double pole single throw switch can be formed by the switches 74 and 76. Relay 72 is known in the art as a latching relay.

Referring now to a preferred embodiment shown in Figure 5, 82 is a bimetallic element which moves to the right when an arc forms between it and electrode 84. A stop is provided for element 82 so that it cannot move too far to the right. 86 is another bimetallic element that moves toward 82 when an arc forms between elements 82 and 86 or their respective contacts 88 and 90. With switch 38 in the open position, current flows through current limiting device 34, ballast 30, contacts 88 and 90 and electrodes 14 and 16 causing the electrodes to stay warm. The voltage between electrode 84 and contact 90 is insufficient to cause an arc to form between them, and due to the physical placement of element 86, an arc never forms between the electrode 84 and the element 86. When switch 38 is closed, the voltage between 84 and 82 is sufficient to cause an arc between them causing element 82 to heat and break contacts 88 and 90. This causes a high back electromotive force to develop between electrodes 14 and 16 and ignite the glow discharge device 12. If the glow discharge device 12 does not ignite, the voltage between contacts 88 and 90 is sufficient to cause an arc between them. The heat developed causes element 86 to move, again closing contacts 88 and 90. The arc between elements 82 and 86 will be extinguished and element 86 will cool and move away from element 82 which will again cause a high back electromotive force across electrodes 14 and 16. This will repeat itself until ignition occurs or switch 38 is opened. It should be noted that as long as switch 38 is closed and light 12 is on, the arc between electrode 84 and contact 88 is maintained. When switch 38 is opened, the voltage between electrode 84 and element 82 becomes insufficient to maintain an arc and element 82 moves toward element 86 closing contacts 88 and 90 extinguishing the arc between electrodes 14 and 16.

Since from the foregoing, the construction and advantages of these quick starting arrangements for fluorescent lamps will be readily apparent, further description is believed to be unnecessary.

However, since numerous modifications will readily occur to those skilled in the art after a consideration of the foregoing specifications and accompanying drawings, it is not intended to limit the invention to the precise embodiments shown and described, but all suitable modifications and equivalents which fall within the scope of the appended claims may be readily included.

Having described the invention, what is claimed as new is:

1. A quick starting arrangement for fluorescent lamps, said fluorescent lamp comprising a hot cathode type of glow discharge device having electrodes at each end between which a light producing discharge takes place, heating means for said electrodes connected thereto, said means being incapable of starting and incapable of maintaining said light producing discharge, switch means for applying to said glow discharge device a potential sufficient to start said light producing discharge therethrough instantly, said switch means controlling the application and removal of said potential while having said electrode heating

means effective, said switch means comprising a manually operable switch positioned within a shunt across a current limiting device, and relay means responsive to the position of said manually operative switch applying said potential to said electrodes to start said light producing discharge when said switch is in a circuit closed position, said relay means comprising a normally closed solenoid operated switch electrically connected to said glow discharge device.

2. A quick starting arrangement for fluorescent lamps, said fluorescent lamp being operatively connected to opposed leads from a power source comprising a hot cathode type of glow discharge device having electrodes at each end between which a light producing discharge takes place, heating means for said electrodes connected thereto, said means being incapable of starting and incapable of maintaining said light producing discharge, switch means for applying to said glow discharge device a potential sufficient to start said light producing discharge therethrough instantly, said switch means controlling the application and removal of said potential while having said electrode heating means effective, said switch means comprising a manually operable switch positioned within a shunt across a current limiting device, and relay means responsive to the position of said manually operative switch applying said potential to said electrodes to start
